AUTOMATIC PUMPING

Robert P. Miller, San Gabriel, Calif.

Application August 15, 1938, Serial No. 224,887

10 Claims. (Cl. 103—234)

This invention relates to automatic pumping of fluid by fluid pressure; the present application being a continuation in part of my copending application Ser. No. 56,492, filed Dec. 28, 1935, now abandoned. The fluid which is to be pumped is herein referred to as the production fluid; and the fluid under pressure which pumps the production fluid is herein referred to as the displacement fluid.

The invention is particularly applicable to petroleum wells in which the production fluid comprises gaseous and/or liquid constituents, and the liquid constituents are oil and/or water. The displacement fluid may be any suitable gas under pressure supplied from any desired source at the top of the well. In practice, flow tubing for production fluid may extend through usual well casing to the production zone of the well, with displacement fluid supplied via the annular space between the tubing and the surrounding casing, or the flow tubing may surround an inner conduit through which displacement fluid is supplied.

The invention relates to that method of pumping in which a foot valve controls admission of production fluid to the flow tubing, and a head valve controls admission of displacement fluid for elevating the previously admitted production fluid. Pumping is automatic, the head and foot valves being dependently actuated and alternately opened and closed responsive to pressure differential. At the start of the filling period, pressure in the flow tubing is relieved by discharge of an elevated slug of production fluid so that formation pressure exceeds pressure in the tubing string and thus creates pressure differential for opening the foot valve and closing the head valve. Production fluid then enters and rises in the flow tubing until pressure in the tubing string plus pressure of displacement fluid opposing opening of the foot valve exceeds formation pressure and thus creates pressure differential in the opposite direction for closing the foot valve and opening the head valve. This inaugurates the discharge period during which displacement fluid forms a fluid piston for elevating and expelling the production which has been trapped in the flow tubing. As the production fluid is elevated and expelled, the displacement fluid expands and thereby relieves pressure in the tubing string until said pressure is again exceeded by formation pressure for opening the foot valve and closing the head valve to restart the filling period.

Cyclic operation is thus dependent upon pres- 55

sure differential inaugurating the filling period, with this pressure differential then automatically decreasing until there is pressure differential in the opposite direction, thereby terminating the filling period and inaugurating the discharge period; and such automatic variation in pressure differential is dependent upon the relation between the well's formation pressure, its productive rate of liquid and of gas, pressure of displacement fluid admitted to the flow tubing, pressure of displacement fluid opposing opening of the foot valve, pressure drop past the open foot valve, and relief of pressure in the flow tubing when production fluid has been elevated and expelled. Consequently, there must be proper relation between these variable factors for each particular installation if automatic cyclic operation is to be maintained.

For example, at each particular installation 20 the relation between these variable factors must be such that: (1) displacement fluid is admitted at a pressure and in a quantity sufficient to elevate that volume of production fluid which has been trapped in the flow tubing; (2) displacement fluid is admitted at a rate not in excess of discharge capacity of the flow tubing (since otherwise expulsion of production fluid would not sufficiently relieve pressure in the flow tubing to permit reopening of the foot valve); and (3) 25 pressure drop past the open foot valve and/or pressure of displacement fluid opposing opening of the foot valve is such as to reverse the direction of pressure differential (for closing the foot valve and opening the head valve) when the volume of production fluid which has entered the tubing string is such that the displacement fluid which is then admitted to the tubing will elevate this production fluid as a slug, without blowing through the column of production fluid 30 and without delay in inaugurating the discharge period.

Furthermore, if automatic cyclic operation is to be maintained as well conditions change during the producing life of the well, the relation 45 between the aforesaid variable factors must be adjusted in accordance with the changed well conditions. For example, as the well's formation pressure and/or its productive rate of liquid and/or gas changes during the producing life of the well, pressure drop past the open foot valve and/or pressure of displacement fluid opposing opening of the foot valve must be adjusted in order to maintain that relation to formation pressure which will close the foot valve and open the head valve after a filling period of desired

time interval; and if there has been a change in discharge capacity of the flow tubing (resulting from employment of a different length and/or diameter of tubing string) it may be necessary to change the rate of admission of displacement fluid in order to maintain necessary relationship to discharge capacity of the flow tubing.

It is the object of the invention to first determine well conditions at each particular installation, and then install a pump so proportioned that rate of admission of displacement fluid, pressure drop past the open foot valve and/or pressure of displacement fluid opposing opening of the foot valve are such as to maintain automatic cyclic operation in accordance with conditions at the particular well.

It is a further object of the invention to adjust the pump subsequent to initial installation, as well conditions (when employing this type of pump) are more accurately determined and/or as well conditions change during the life of the well, so that the aforementioned operating factors may be adjusted in accordance with particular well conditions.

It is a still further object of the invention to adapt the pump to a particular installation by interchangeably employing pump structures having their parts variously proportioned so as to provide different relationships between the aforementioned operating factors; and to adjust such a pump to changed well conditions by pulling the tubing string and installing a different pump assembly.

It is a still further object of the invention to adapt the pump for adjustment from the earth's surface while the pump is in the well, so as to avoid the necessity of pulling the tubing string in order to adapt the pump to particular well conditions.

It is a still further object of the invention to provide for adjustment by a combination of interchangeable parts and adjustment from the earth's surface, whereby adjustments to meet transient conditions may be made without pulling the tubing string, while adjustments to meet changed conditions which are liable to be more permanent may be made by pulling the tubing string and substituting interchangeable parts.

It is a still further object of the invention to arrange the dependently actuated foot and head valves of the pump as a simple but reliable valve mechanism.

It is a still further object of the invention to arrange the pump so that it is particularly applicable to an installation wherein the displacement fluid is supplied via the annular space between the flow tubing and a surrounding well casing with a packer in said annular space confining the displacement fluid; and with the valve mechanism adapted for installation at any desired level adjacent or appreciably below the packer and arranged whereby an extremely simple assembly connects the valve mechanism with the annular space above the packer, with said assembly offering only minimum restriction to discharge capacity of the flow tubing.

Further objects of the invention will be readily understood from the following description of the accompanying drawings, in which:

Fig. 1 is a vertical section through the upper portion of a well in which the pump is installed, showing the adjusting mechanism at the earth's surface.

Fig. 2 is a similar section through the lower portion of the well, showing the pump assembly.

Fig. 3 is a detail axial section through the pump structure.

Fig. 4 is a transverse section on the line 4-4 of Fig. 3.

Fig. 5 is a detail side elevation of actuating mechanism for adjusting the pump.

By way of example, the invention is illustrated and described in connection with the pumping of petroleum wells, the pump being installed in flow tubing A which in the present embodiment of the invention is surrounded by well casing A' so that the annular space 3 between the tubing and the casing forms a supply conduit for the gas under pressure which constitutes the displacement fluid. The displacement fluid may be supplied to the space 3 from an upper gas zone of the well or from a conduit 2 at the earth's surface leading from any source of supply; and by means of a packer 4 the annular space 3 is shut off from the production fluid which enters the well casing from the production zone of the well. The production fluid enters the well casing via a perforated casing section 2a which is below the packer 4 and flows thence through an oil screen 5 at the lower end of the flow tubing, seeking its static or working level in the flow tubing.

Valve mechanism comprising a dependently actuated head and foot valve is mounted in the flow tubing. The foot valve B controls admission of production fluid to that portion of the flow tubing which is above the screen 5 and the head valve C controls admission of displacement fluid from the annular space 3 to that portion of the flow tubing which is above the foot valve B.

The valve mechanism B-C is adapted for mounting in the flow tubing A at any desired distance below the packer 4, whereby the pump may be operated at a level appreciably below the packer or may be operated at a level adjacent the packer. Means for supplying displacement fluid from the annular space 3 above the packer, to the head valve C below the packer, is arranged for simplicity and economy of construction and so as to offer minimum obstruction to elevation of production fluid via the flow tubing A.

As an instance of this arrangement, a section 6 of the flow tubing may be ported for admitting displacement fluid from the space 3 to a sleeve 7 which is concentrically mounted in the section 6 and which is surrounded by passageways 8 opening longitudinally through said section; and a conduit 9 may be detachably suspended from the sleeve 7 concentrically within the flow tubing. A section 10 of the flow tubing is detachably suspended from the section 6, and is in turn detachably connected to a section 11 of the flow tubing from which the screen 5 is suspended, with the section 11 forming a housing for the valve mechanism B-C. The upper portion of the housing 11 has a sleeve 13 mounted therein, with the valve mechanism B-C suspended from said sleeve and with passageways 14 open longitudinally through the housing 11 around the sleeve.

The packer 4 is positioned below the ported section 6, preferably adjacent the upper end of the section 10; and sections 10 of different length may be interchangeably incorporated in the flow tubing so as to position the housing 11 and the valve mechanism B-C either a short distance or any desired appreciable distance below the packer 4. A conduit 12 is detachably connected to the conduit 9 and to the bore of the sleeve 13,

whereby conduits 9—12 of different bore, and/or of different length depending upon the length of the section 10, may be interchangeably employed for a purpose hereinafter described. In the illustrated embodiment, the conduits 9—12 are telescopically connected with suitable packing 15 at their telescopic joint.

Displacement fluid for operating the pump is supplied via the conduits 9—12 to the bore of the sleeve 13 and thence to the communicating head valve C. This supply of displacement fluid need have only a relatively small cross-sectional area compared with the cross-sectional area of the flow tubing A. Consequently, by positioning the conduits 9—12 within the flow tubing the required cross-sectional area for the displacement fluid is obtained while employing conduits 9—12 which are of relatively small diameter, thereby requiring conduits of no great wall strength in order to withstand pressure in said conduits, and with said conduits offering but little restriction to flow through the surrounding tubing string A.

For a purpose hereinafter described, the rate of admission of displacement fluid via the ported section 6 may be adjusted. For this purpose, a series of longitudinally spaced lateral parts 40 may open through the section 6 from the space 3 to the interior of the sleeve 7, with each successively lower port of increased diameter; and a plug 41 may be rotated in the sleeve 7 for selectively opening communication between the respective ports 40 and the conduits 9—12. As an instance of this arrangement, the plug 41 has an axial bore 42 communicating at its lower end with the conduit 9. Above said lower end, the bore 42 is of progressively reduced diameter in transverse alignment with the respective ports 40; and in transverse alignment with each of said ports the bore 42 has the same diameter as said port, with the upper end of the bore closed at a level above the uppermost port. Radial ports 43 are formed in the plug 41 in longitudinally spaced relation so as to provide communication between the respective ports 40 and their respective transversely aligned portions of the bore 42, and each of the ports 43 has the same diameter as its corresponding portion of the bore 42 and its corresponding port 40.

The radial ports 43 are relatively arcuately spaced, preferably equidistantly, whereby in one rotatably adjusted position of the plug 41 the uppermost port 43 provides communication between its cooperating port 40 and the bore 42 while the other ports 40 are closed by the plug 41 (as shown at Figs. 3 and 4). As the plug 41 is rotated step-by-step, communication is successively established via the respective successively lower cooperating ports 40—43, while closing communication via the remainder of said cooperating ports; and after communication has been established via the lowermost ports 40—43 the next step-by-step rotation of the plug 41 reestablishes connection via the uppermost ports 40—43 for repeating the cycle of adjustment. Since each pair of the successively lower cooperating ports 40—43 are of increased diameter, step-by-step rotation of the plug 41 provides an adjustment for successively increasing the cross-sectional area of the displacement fluid which is admitted to the bore 42 and thence to the conduits 9—12.

The plug 41 may be rotated step-by-step, by depressing an actuating head 44. As an instance of this arrangement, a stem 45 may project up-

wardly from the plug 41, with the actuating head 44 yieldably projected relative to the stem 45 while fixed for rotation with said stem. For this purpose the stem 45 is slideable in a bore 46 of a sleeve 47 which depends from the actuating head 44, with said stem and bore of corresponding polygonal cross-section and with a spring 48 mounted in said bore between the stem 45 and the actuating head 44. The sleeve 47 and the stem 45 are rotatable in an extension 7^a of the sleeve 7, there being an operating connection between the sleeve 47 and the sleeve 7^a whereby depression of the head 44 rotates the sleeve 47 and the stem 45 for turning the plug 41 through one of its step-by-step arcs of rotation.

As an instance of this operating connection, the outer periphery of the sleeve 47 is grooved, and pins 50 project from the sleeve 7^a into said groove. The groove comprises a plurality of groove elements equi-distantly circumferentially spaced around the sleeve 47 and corresponding in number to the number of cooperating ports 40—43. Each groove element comprises cooperating longitudinal grooves 51—52, the groove 51 being curved at its lower end as shown at 53 so as to form a space 54, with this space laterally offset with relation to the groove 51. The groove 52 projects upwardly from the space 54 with the lower end of said groove in longitudinal alignment with said space as shown at 55, and with said groove then inclined relative to the groove 51 and terminating at its upper end in a space 56. The space 56 of each of the groove elements is in longitudinal alignment with and forms the upper end of the groove 51 of the next groove element.

When the head 44 and its sleeve 47 are upwardly spring-projected with relation to the stem 45 and the sleeve 7^a as shown at Fig. 3, each pin 50 is in the space 54 of one of the groove elements 51—52. The pin is thus in longitudinal alignment with the entrance 55 to the groove 52 of said groove element and is laterally offset relative to the groove 51 of said groove element. When the head 44 and the sleeve 47 are longitudinally depressed against the tension of spring 48, the pin 50 enters and then moves upwardly along the inclined groove 52 and into the space 56, so that when the head 44 is then released for spring elevation of the sleeve 47 relative to the stem 45 and the sleeve 7^a, the pin 50 enters and moves downwardly along the groove 51 of the next one of the groove elements 51—52, and thence along the curved surface 53 and into the space 54 of said next groove element. Since the pins 50 project from the sleeve 7^a which is fixed against rotation, the sleeve 47 is turned relative to the sleeve 7^a by this movement of the pin 50 along an inclined groove 52 and then along the curved lower end of the next groove 51, with the stem 45 and the plug 41 turning with the sleeve 47. This turning of the plug 41 moves the same from a position aligning one of the pairs of cooperating ports 40—43, to a position aligning the next pair of said cooperating ports. In similar manner, when the head 44 is again depressed and then released for spring projection, the pin 50 moves along the next groove 52 and then along the next groove 51, for turning the plug 41 to a position aligning the next pair of cooperating ports 40—43.

The displacement fluid which is admitted via a pair of cooperating ports 40—43 and supplied thence via conduits 9—12 to the bore of the sleeve 13, is admitted to the housing 11 via the

head valve C. The head valve may be of the type disclosed and claimed in my copending application Ser. No. 334,856, filed May 13, 1940; and is illustrated as comprising a cylinder 20 suspended from and communicating at its upper end with the bore of the sleeve 13, with the lower end of the cylinder closed by a bushing 21, and with a valve sleeve 22 projecting upwardly from a cage 26 and adapted for reciprocation on the cylinder 20. When the sleeve 22 is in its upper position as shown at Fig. 3 it closes lateral ports 23 in the wall of cylinder 20 and thus shuts off admission of displacement fluid to the housing 11, and when in its lower position it uncovers the ports 23 so as to admit displacement fluid to the housing 11. A replaceable baffle 24 may reciprocate with the sleeve 22 so that the displacement fluid which is discharged via the ports 23 strikes the baffle, instead of impinging directly against the wall of the housing 11, as might prematurely cut-out the housing.

When the head valve is closed, pressure of displacement fluid supplied via 9-12 preferably tends to open the valve, and for this purpose a pin 27 may project from the cage 26, through the bushing 21 and into the cylinder 20. Pressure of displacement fluid is thus directed against the end of the pin 27, thereby exerting a force tending to lower the sleeve 22 so as to uncover the ports 23, and the force which is thus exerted is dependent upon the pressure of the displacement fluid supplied via 9-12 and the pressure area of the pin 27. The pin 27 is preferably detachably supported by the cage 26 whereby pins having different pressure areas may be interchangeably employed for a purpose hereinafter described; and the bushing 21 through which the pin 27 projects is also detachable so that a bushing may be employed having a bore adapted for snug sliding reception of the particular diameter of pressure pin which is being used.

The head valve C is adapted for dependent actuation with the foot valve B, so that when the foot valve is closed the discharge ports of the head valve are uncovered and when the foot valve is open the discharge ports of the head valve are closed. For this purpose, a valve stem 28 depends from the cage 26 of the reciprocating head valve and is connected to the valve head of the foot valve.

The foot valve B controls admission to the housing 11 of production fluid which enters the lower portion of the tubing string via the screen section 5. The foot valve comprises a valve head 30 suspended from valve stem 28 and a cooperating valve seat 31. The valve seat is fixed in the lower portion of the housing 11 and has an axial bore 32 and a transverse seating surface 33. The cooperating valve head 30 is adapted for reciprocation in the bore 32 and has an annular flange 34 adapted to seat on the surface 33 for closing the foot valve. Opening movement of the valve head is preferably limited so that when the foot valve has been opened to its limit of movement as shown at Fig. 3, the head 30 is not clear of the bore 32 but still offers some restriction to free flow of fluid through the open valve; and the valve head is of such diameter as to provide a restricted annular space between the same and the surrounding wall of the bore 32 in order to restrict free flow of fluid past the valve during its closing movement.

The valve head 30 is detachably mounted on its valve stem and for this purpose a threaded bushing 35 may detachably connect the valve

head to the valve stem 28, preferably with the connection adapting the valve head for rotation relative to its stem. Valve heads of different diameter may thus be interchangeably mounted on the valve stem, to adjust the restricted annular space between the valve head and the cooperating bore of the valve seat for a purpose herein-after described.

Operation of the structure thus far described, is as follows:

Formation pressure tends to open the foot valve B and close the dependently actuated head valve C. This pressure is opposed by pressure of displacement fluid against the pressure pin 27. These opposing pressures are such that when pressure in the flow tubing is relieved by elevating and expelling a slug of production fluid, pressure differential opens the foot valve and closes the dependently actuated head valve. Production fluid is thus admitted to the housing 11 via the open foot valve B and rises in the flow tubing, seeking its static or working level.

At first the rate of admission of production fluid is comparatively slow since its entrance is opposed by back pressure of that column of displacement fluid which is in the flow tubing and which has expelled a slug of production fluid but which has not yet been completely discharged at the top of the well. As this displacement fluid is expelled, thereby relieving back pressure, the rate of admission of production fluid increases until all of the production fluid which has accumulated in the well during the preceding discharge period has entered the flow tubing. Then the rate of admission of production fluid equals the productive rate of the well, and diminishes as the productive rate decreases as a result of the increasing back pressure of the rising column of production fluid.

During this varying rate of intake of production fluid the open foot valve partially restricts flow so as to maintain pressure drop past the open valve. This pressure drop is so great that in spite of the rising column of production fluid and pressure of displacement fluid against the pin 27, pressure differential (for retaining the foot valve in open position) is maintained until the production fluid stands in the flow tubing at that level which provides a column of such maximum volume that the subsequently admitted displacement fluid will be capable of elevating and expelling the same but of such minimum volume that the displacement fluid will not blow through the column of fluid. However, the pressure drops past the open foot valve is not so excessive but that as soon as the production fluid reaches the aforementioned level, pressure of the column of fluid plus pressure of displacement fluid against the pin 27 exceeds formation pressure and thereby immediately closes the foot valve and opens the dependently actuated head valve.

Displacement fluid is then admitted to the housing 11 via the open head valve C, at a pressure and in quantity sufficient to elevate that volume of production fluid which is now trapped in the flow tubing above the closed foot valve B. The displacement fluid thus elevates the production fluid as a slug, and discharges the same at the top of the well. The rate of admission of displacement fluid is such that it does not exceed discharge capacity of the flow tubing, i. e. it is such that when production fluid is expelled, pressure in the flow tubing is relieved rather than being maintained by the incoming displace-

ment fluid. Due to this relief of pressure, formation pressure in the well again exceeds pressure in the flow tubing plus pressure of displacement fluid against the pin 27, so that resulting pressure differential reopens the foot valve and closes the dependently actuated head valve, thereby re-starting the filling period.

Automatic cyclic operation is thus dependent upon the pump having its parts proportioned in accordance with well conditions of each particular installation, i. e. discharge capacity of the tubing string and formation pressure and productive rate of each particular well. Consequently, before installing a pump well conditions at that particular installation are surveyed to determine these variable factors.

The pump, as then installed, is provided with a foot valve B which will insure a predetermined restriction to flow past the open valve as it approaches closed position, i. e. as the valve head 30 moving into the bore 32 further restricts the annular space between the valve head and the surrounding bore. For this purpose, the valve head 30 which is mounted on the valve stem 28 is of such diameter as to provide a predetermined restricted passageway between the valve head and the surrounding bore 32, with opening movement of the valve head so limited by abutment of the cage 26 against the bushing 21 that when the foot valve is open it still maintains a predetermined restricted passageway between the valve head and its cooperating seat. This restricted passageway is determined with relation to (1) productive rate of gas and of liquid and formation pressure of the particular well, (2) pressure of displacement fluid admitted to the flow tubing, and (3) pressure of displacement fluid opposing opening of the foot valve. In accordance with these factors the restricted passageway provides such pressure drop past the open foot valve as it approaches closed position that (1) formation pressure is not exceeded by opposing pressure tending to close the foot valve for terminating the filling period, until production fluid has been admitted in such volume that the subsequently admitted displacement fluid will not blow through the column of production fluid but will elevate and expel the same as a slug, and (2) formation pressure is exceeded by said opposing pressure (thereby closing the foot valve) as soon as said volume of production fluid has been admitted.

Furthermore, the pump is arranged so that displacement fluid supplied via conduits 9-12 exerts predetermined pressure opposing opening of the foot valve. For this purpose, a pin 27 of selected pressure area is mounted on the cage 26 for projection into the cylinder 20. This pressure area is determined with relation to (1) pressure of displacement fluid supplied via conduits 9-12 and (2) pressure drop past the open foot valve, so that the force exerted at said pressure area in cooperation with pressure drop past the open foot valve is (1) exceeded by formation pressure for maintaining the foot valve open until the desired volume of production fluid has been admitted to the flow tubing, and (2) exceeds formation pressure for closing the foot valve as soon as the desired volume of production fluid has been admitted.

Furthermore, the pump is arranged so as to provide a predetermined rate of admission of displacement fluid. For this purpose, the displacement fluid may have a predetermined cross-sectional area of admission, or the rate of admission

may be controlled by imposing frictional resistance through different lengths of admission conduit, or a combination of such regulating means may be employed. For example, the rate of admission of displacement fluid may be regulated by employing a conduit 9-12 of selected cross-sectional area, with the tubing section 10 of such longitudinal dimension that the conduit 9-12 is telescoped to a selected length. Furthermore, the rate of admission of displacement fluid may be regulated by depressing and then releasing the head 44 the desired number of times before installing the pump in the well, so as to turn the plug 41 for alinement of those cooperating ports 40-43 which provide desired cross-sectional area for admission of fluid. A combination of the aforementioned adjusting means may also be employed.

The selected rate of admission of displacement fluid is determined with relation to (1) pressure of displacement fluid supplied to the annular space 3, and (2) discharge capacity of the tubing string (as determined by length and bore of the tubing string and back pressure maintained on the well by a gas trap or the like), so that the rate of admission of displacement fluid will not exceed the discharge capacity of the tubing string. This is to insure relief of pressure and opening of the foot valve and closing of the dependently actuated head valve as soon as a slug of production fluid has been elevated and expelled.

If the rate of admission of displacement fluid exceeded discharge capacity of the tubing string, pressure would be maintained in the flow tubing after elevation and expulsion of the slug of production fluid, thereby tending to maintain the foot valve closed and the head valve open. If the input of displacement fluid to the annular space 3 were so great as to maintain this pressure, the pressure in the flow tubing would never be sufficiently relieved to restart the filling period, and the pump would become inoperative with displacement fluid continuing to enter the flow tubing via the open head valve and flowing thence via the flow tubing for escape at the top of the well. On the other hand, if the input of displacement fluid to the annular space 3 were so restricted as to reduce the pressure in said annular space as a result of the displacement fluid continuing to flow via the open head valve for escape via the flow tubing, the pressure in the annular space 3 and in the tubing would eventually be relieved to the extent necessary to restart the filling period. But this would only occur after an appreciable delay in restarting the filling period, during which displacement fluid would continue to escape, and there would also be appreciable delay in restarting the next following discharge period, since it would be necessary for the pressure to again build up in the annular space 3 before it would be sufficient to elevate the slug of production fluid which had been trapped in the flow tubing during the preceding filling period.

Furthermore, when the pump has been installed and is ready for operation, the pressure at which displacement fluid is supplied to the space 3 is regulated with relation to volume of production fluid which is admitted to the flow tubing during the filling period, and with relation to the pressure area of the pin 27, so that the foot valve will be automatically closed and the dependently actuated head valve opened at the end of the desired filling period, with the pressure of the displacement fluid (which is then admitted to

the flow tubing) sufficient to elevate and expel production fluid at the desired speed.

With the pump installed in accordance with conditions at the particular well (as above described) it will continue to automatically operate as long as well conditions remain substantially unchanged. But appreciable change in productive rate of gas and/or liquid or appreciable change in formation pressure or appreciable change in discharge capacity of the tubing string, will destroy the predetermined relation between the various operating factors.

Therefore as the productive rate of the well decreases or its formation pressure diminishes, the foot valve B may be provided with a head 30 of greater diameter providing a greater restriction to flow and consequently an increased pressure drop past the open foot valve as it approaches closed position; the head 30 which is selected being such as to provide a pressure drop which with relation to the changed well conditions will restore the previously described operating cycle.

In lieu of, or in conjunction with adjustment of pressure drop past the open foot valve as it approaches closed position, a pressure pin 27 of smaller pressure area may be installed when productive rate or formation pressure of the well decreases. This reduction in pressure area will be that required for restoring the proper relation between the various operating factors for continuing automatic cyclic operation under the changed well conditions.

In similar manner, if changing well conditions make it advisable to supply displacement fluid to the annular space 3 at a different pressure or if the discharge capacity of the tubing string changes, the rate of admission of displacement fluid is restored to its proper relation to discharge capacity of the tubing string, by substituting a different bore and/or length of conduit 9-12, and/or rotating the plug 41 for alining a different pair of cooperating ports 40-43.

It is thus possible by one or more of the aforementioned adjustments, to restore that operating relationship in accordance with changed well conditions, which will continue automatic cyclic operation of the pump.

The adjustments which have been described are made by pulling the tubing string A when it is desired to change the valve head 30 or the pressure pin 27 or the conduits 9-12, or when it is desired to turn the plug 41 for alining a different pair of cooperating ports 40-43. The invention also provides for adjusting the pump to particular well conditions without pulling the tubing string.

For this purpose, means may be provided at the earth's surface for building up pressure in the tubing string A during the filling period of the pump, with this pressure relieved during the discharge period of the pump. Consequently, without changing the valve head 30 so as to provide different restriction to flow past the open foot valve B and/or without changing the pressure pin 27 so as to provide different pressure of displacement fluid opposing opening of the foot valve, such pressure may be built up in the tubing string during the filling period as will insure terminating the filling period and inaugurating the discharge period for maintaining automatic cyclic operation in accordance with the particular well conditions at each installation.

As in instance of this arrangement, the tubing string A may be provided with an usual manu-

ally controlled valve 60 at the earth's surface (with said valve open during operation of the pump), and may also be provided at the earth's surface with a valve 61 which is respectively opened and closed during discharge and filling periods of the pump and which may be automatically timed. The valve 61 is open during the discharge period of the pump so that at the end of said discharge period pressure in the tubing string is relieved (as previously described) and formation pressure thereby opens the foot valve B to inaugurate the filling period; and the valve 61 is closed for a desired interval during the filling period of the pump so as to build up pressure in the tubing string for insuring said pressure exceeding formation pressure and thus closing the foot valve and inaugurating the discharge period as soon as the desired volume of production fluid has entered the flow tubing.

Automatic timing of the valve 61 may be by a diaphragm control 62, the valve being opened by a spring (not shown) when pressure against the diaphragm is relieved via a bleeder line 63, and being closed by pressure against the diaphragm when the bleeder line is closed. Pressure for actuating the diaphragm may be supplied via a line 64 which may be a branch of the conduit 2 which supplies displacement fluid to the annular space 3 and which may have suitable pressure regulating means 64a; and the line 64 may have a branch leading therefrom and forming the bleeder line 63. The bleeder line 63 may be alternately opened and closed by a valve 65 which may be actuated by a usual clock mechanism. For example, a clock mechanism 66 may rotate a disc 67, and the valve 65 may be mounted on a lever 68 which rides on the periphery of the rotating disc. The periphery of the disc has alternate high and low spots 69 and 70, whereby engagement of the lever by a high spot opens the valve 65, and engagement of the lever by a low spot closed the valve as shown at Fig. 1.

The disc 67 is readily detachable from the shaft of the clock mechanism whereby discs may be interchangeably employed having alternate high and low spots of different length. A disc is selected having its alternate high and low spots of such relative length as to open and close the bleeder line 63 and thereby open and close the valve 61 for desired time intervals during the discharge and filling periods of the particular pump, so as to build up pressure for terminating the filling period and inaugurating the discharge period in accordance with operating factors of the particular installation.

A by-pass 71 is preferably provided around the valve 61 and is normally closed by a pressure relief valve 72. If, through any mechanical defect the valve 61 fails to open at the proper time and excess pressure is thus built up in the flow tubing A, the valve 72 automatically opens to relieve said excess pressure via the by-pass, so that only the desired pressure is built up in the flow tubing.

If, while the valve 61 is closed during the filling period, pressure of production fluid in the tubing string A is insufficient to build up the desired pressure, additional fluid pressure may be supplied to the tubing string. For this purpose, a line 73 may supply fluid pressure to the flow tubing A and may be a branch line leading from the conduit 2 which supplies displacement fluid to the annular space 3. The line 73 may be controlled by a valve 74 at the earth's surface with

this valve respectively opened and closed while the valve 61 is closed and open respectively.

Automatic timing of the valve 74 in synchronism with the valve 61 may be by a diaphragm control 75, the valve 74 being closed by a spring (not shown) when pressure against the diaphragm 75 is relieved, preferably via the previously described bleeder line 63, and the valve 74 being opened by pressure against the diaphragm when the bleeder line is closed. For this purpose, a branch line 76 may connect the line 64 with the diaphragm 75. The clock mechanism 66 thus actuates the valves 61 and 74 in synchronism, whereby fluid pressure is supplied via the line 73 to the tubing string A while the valve 61 is closed, in order to build up desired pressure in the tubing string, and the supply of fluid pressure via the line 73 is shut off while the valve 61 is in open position for discharging production fluid from the tubing string.

When the pump is to be operated without fluid pressure being supplied via the line 73, a valve 77 in the line 76 is closed at a time when the valve 74 is in its closed position, i. e. at a time when the valve 65 is in position opening the bleeder line 63. The closed valve 77 thus prevents fluid pressure being subsequently supplied via the line 76 for opening the valve 74, and admission of fluid to the tubing string via the line 73 is thus shut off.

The line 73 may also be employed for "kick-over" at the start of pumping operations, i. e. for supplying fluid pressure via the tubing string A and thence via the open head valve C to the annular space 3 for discharge from said space at the earth's surface. For this purpose a line 80 having a manually controlled valve 81 may lead from the annular space 3 and may communicate with the by-pass 71. During pumping operation the valve 81 is closed for preventing escape of pressure via the line 80; but for "kick-over" at the start of pumping operations a valve 82 in the supply conduit 2 is closed and the valve 81 in the line 80 is opened, and the bleeder line 63 is closed and the valve 77 is opened so that the valve 74 is opened by pressure against its diaphragm 75, while the valve 61 is closed by pressure against its diaphragm 62.

Pressure fluid supplied via the open valve 74 thus flows downwardly through the tubing string A so as to close the foot valve B and open the dependently actuated head valve C, whereby said fluid is discharged via conduits 9-12 and the ported section 6 to the annular space 3, from whence it is discharged via the line 80 and the by-pass 71, the relief valve 72 having been opened to permit free discharge of the fluid via the by-pass. After "kick-over" the valve 82 is opened and the valve 81 is closed, and the relief valve 72 is set to open at any desired excess pressure, so that the pump is ready for automatic cyclic operation.

Operation, when employing the automatically timed valve 61 (together with the synchronized valve 74 when so desired) is as follows:

The operating factors of the particular well are determined, and in accordance with these particular conditions a pump is installed providing predetermined restriction to flow past the open foot valve B as it approaches closed position and having a pressure pin 27 of predetermined pressure area and providing a predetermined rate of admission of displacement fluid via ported section 6 and conduits 9-12, so as to insure automatic cyclic operation as previously described.

However, as soon as the pump is installed it may be found that while production rate of liquid is as has been determined by prior survey of well conditions, productive rate of gas is appreciably increased when operating the pump, due to the pump functioning with its foot valve B closed during the discharge period and thus preventing back pressure against the formation. Such increase in productive rate of gas changes the particular relationship between the various operating factors for which the pump has been proportioned, i. e. the unforeseen increased flow of gas may increase pressure drop past the open foot valve B as it approaches closed position so that pressure in the tubing string will not exceed formation pressure (for closing the foot valve) at the end of a desired filling period.

Furthermore, it is preferable when first installing the pump to employ a valve head 30 of greater diameter than required for proper functioning of the pump, since reduction in productive rate of the well during its producing life will eventually make necessary a larger valve head 30 in order to provide greater restriction to flow past the open foot valve as it approaches closed position for maintaining desired pressure drop in accordance with changed well conditions, and initial installation of a valve head 30 of greater diameter than required will thus postpone the necessity of substituting a larger valve head as well conditions change. But such initial use of a valve head of greater diameter than required, will initially produce excess pressure drop past the open foot valve B as it approaches closed position so that the foot valve will not close at the end of a desired filling period.

Furthermore, decrease in productive rate and/or formation pressure of the well during its producing life, will eventually destroy the desired relationship between the various operating factors so that pressure in the tubing string plus pressure of displacement fluid against the pin 27 and opposing opening of the foot valve will no longer exceed formation pressure at the end of a desired filling period, and consequently there will be undue delay in closing the foot valve to inaugurate the discharge period.

To compensate for the aforementioned conditions and thus maintain automatic cyclic operation without pulling the tubing string and substituting a different valve head 30 and/or a different pressure pin 27, the valve 61 is automatically opened and closed at selected time intervals during operation of the pump. For this purpose, a disc 67 is selected which will provide a desired time interval during which the valve 61 is open, followed by a desired time interval during which the valve is closed.

The selection of a disc 67 is such that the valve 61 remains open during the discharge period of the pump, until the slug of production fluid which has been discharged via the open valve and pressure of displacement fluid which has elevated the slug has been so relieved via the open valve, that formation pressure again exceeds pressure in the tubing string plus pressure of displacement fluid against the pin 27 for opening the foot valve and closing the dependently actuated head valve to inaugurate the filling period.

The selection of a disc 67 is also such that during the filling period the valve 61 is closed for such time interval as to build up pressure in the tubing string A, so that if the diameter of the valve head 30 and/or the pressure area of the

pin 27 are not such as to provide necessary pressure in the tubing string for closing the foot valve at the end of a desired filling period, the additional pressure built up as a result of closing the valve 61 will insure the desired pressure in excess of formation pressure for closing the foot valve at the desired time. The selection of a disc 67 is also such that the valve 61 is again opened as soon as the foot valve has closed for terminating the filling period and inaugurating the discharge period.

If sufficient pressure is not built up by closing the valve 61, the valve 74 may be operated in synchronism with the valve 61 so as to admit additional fluid pressure via the line 73 while the valve 61 is closed, thereby insuring the desired pressure being built up in the tubing string for terminating the filling period and inaugurating the discharge period.

Means may also be provided at the earth's surface for adjusting the rate of admission of displacement fluid to the head valve C via the conduits 9-12, without pulling the tubing string A. For this purpose, and without pulling the tubing string to substitute conduits 9-12 of different length and/or bore, and without pulling the tubing string to permit access to the head 44 for adjusting the plug 41 so as to aline a different pair of cooperating ports 40-43, the head 44 may be actuated from the earth's surface while the tubing string is still in the well.

As an instance of this arrangement, a line 90 which is weighted at its lower end as shown at 91, may be reciprocated through the tubing string A by a suitable operating connection (not shown) at the earth's surface. By lowering the line 90 its weight 91 depresses the head 44 against the tension of the spring 48, and by then elevating the line and its weight the head 44 is elevated by its spring. This movement of the head 44 rotates the plug 41 as previously described, so as to aline a different pair of cooperating ports 40-43; and by lowering and then elevating the line 90 any desired number of times the plug 41 is rotated for alining a desired pair of the cooperating ports.

Operation when rotatably adjusting the plug 41 from the earth's surface is as follows:

In accordance with particular well conditions, the pump is initially installed so that during operation of the pump displacement fluid is admitted via the ported section 6 and the plug 41 to the conduits 9-12, with the rate of admission of displacement fluid regulated by the plug 41 having been rotated to aline a selected pair of the cooperating ports 40-43 and/or by conduits 9-12 of selected length and/or bore having been installed in the pump.

During operation of the pump a different rate of admission of displacement fluid may become necessary in order that it shall not exceed discharge capacity of the tubing string A. This may be due to changing discharge capacity of the tubing string resulting from substitution of a different bore and/or length of tubing string, or resulting from different back pressure being maintained in the tubing string at a gas trap or the like with which the tubing string communicates. In order to maintain the desired rate of admission of displacement fluid it may also be necessary to change the cross-sectional area of admission in accordance with change in pressure of the displacement fluid. For example, if the displacement fluid is not supplied via the conduit 2 which leads from a source of supply

having constant pressure, but is supplied from an upper gas zone of the well, the pressure of said fluid will vary in accordance with changing formation pressure at said upper zone.

Admission of displacement fluid is adjusted in accordance with the aforementioned variable factors so as to provide desired rate of admission of displacement fluid for maintaining automatic cyclic operation of the pump. In order to make said adjustment without pulling the tubing string for inserting different conduits 9-12 or for rotating the plug 41 by direct engagement of the head 44, the line 90 is reciprocated from the earth's surface while the tubing string is still in the well, so as to aline that particular pair of cooperating ports 40-43 which has a cross-sectional area insuring desired rate of admission of displacement fluid, in accordance with particular well conditions, for maintaining automatic cyclic operation of the pump.

The invention thus provides for automatic operation by installing the pump in accordance with well conditions at each particular installation, so as to insure pressure differential for inaugurating the filling period, followed by decrease of said pressure differential until the pressure differential is in the opposite direction for starting the discharge period, with displacement fluid admitted during said discharge period so as to elevate and discharge the trapped production fluid, and with discharge of the production fluid relieving pressure so as to restart the filling period.

The invention also provides for adjusting the various operating factors during the producing life of the well and as well conditions change, so as to restore the proper relationship for continuing automatic cyclic operation.

The invention also provides for making such adjustments by pulling the tubing string for substituting interchangeable parts, or for making said adjustments from the earth's surface without pulling the tubing string. Adjustments to meet particular conditions which cannot be accurately determined until the pump is in operation or to meet changed conditions of a transient nature may thus be made from the earth's surface, while adjustments to meet changed conditions which are of a more permanent nature may be made by pulling the tubing string and substituting interchangeable parts.

I claim:

1. In a tubing string, well tubing, an extension suspended from the well tubing, a housing suspended from the extension, the extension being detachably connected to the well tubing and to the housing whereby extensions of different length may be interchangeably employed, an intake for displacement fluid leading to the interior of the tubing string, a valve controlling admission of displacement fluid to the housing, a conduit in the tubing string providing communication between said intake and said valve, said conduit being detachably supported so that conduits of different bore may be interchangeably employed, said conduit comprising telescopic sections whereby it may telescopically adapt itself to the length of the particular extension which is employed, and a valve controlling admission of production fluid to the housing, the said valves being adapted for dependent automatic operation responsive to pressure differential for admitting production fluid to the housing while shutting off admission of displacement fluid and then trapping production fluid

in the housing and admitting displacement fluid for elevating the trapped production fluid and then repeating the cycle of operation.

2. In a tubing string, a housing, an intake for displacement fluid leading to the interior of the tubing string, a valve controlling admission of displacement fluid to the housing, a conduit in the tubing string providing communication between said intake and said valve, said conduit comprising telescopic sections whereby it may be adjusted to a length providing predetermined rate of flow of displacement fluid with relation to discharge capacity of the tubing string, and a valve controlling admission of production fluid to the housing, the said valves being adapted for dependent automatic operation responsive to pressure differential for admitting production fluid to the housing while shutting off admission of displacement fluid and then trapping production fluid in the housing and admitting displacement fluid for elevating the trapped production fluid and then repeating the cycle of operation.

3. In a tubing string, a housing, an intake for displacement fluid leading to the interior of the tubing string, a valve controlling admission of displacement fluid to the housing, a conduit in the tubing string providing communication between said intake and said valve, said conduit being detachably supported so that conduits of different bore may be interchangeably employed, said conduit comprising telescopic sections whereby it may be adjusted to a length so that the conduit is of a length and bore for predetermined rate of flow of displacement fluid with relation to discharge capacity of the tubing string, and a valve controlling admission of production fluid to the housing, the said valves being adapted for dependent automatic operation responsive to pressure differential for admitting production fluid to the housing while shutting off admission of displacement fluid and then trapping production fluid in the housing and admitting displacement fluid for elevating the trapped production fluid and then repeating the cycle of operation.

4. In combination, a tubing string, a valve controlling admission of displacement fluid to the tubing string, a valve controlling admission of production fluid to the tubing string, the said valves being adapted for dependent automatic operation for admitting production fluid to the tubing string while shutting off admission of displacement fluid and then trapping production fluid in the tubing string and admitting displacement fluid for elevating the trapped production fluid for discharge via the tubing string and then repeating the cycle of operation, a valve controlling discharge of the elevated production fluid from the tubing string, and means for respectively closing and opening the last mentioned valve during opening and closing of the second mentioned valve.

5. In combination, a tubing string, a valve controlling admission of displacement fluid to the tubing string, a valve controlling admission of production fluid to the tubing string, the said valves being adapted for dependent automatic operation for admitting production fluid to the tubing string while shutting off admission of displacement fluid and then trapping production fluid in the tubing string and admitting displacement fluid for elevating the trapped production fluid for discharge via the tubing string and then repeating the cycle of operation, a valve control-

ling discharge of the elevated production fluid from the tubing string, and means for automatically opening and closing the last mentioned valve at predetermined time intervals.

5 6. In combination, a tubing string, a valve controlling admission of displacement fluid to the tubing string, a valve controlling admission of production fluid to the tubing string, the said valves being adapted for dependent automatic operation for admitting production fluid to the tubing string while shutting off admission of displacement fluid and then trapping production fluid in the tubing string and admitting displacement fluid for elevating the trapped production fluid for discharge via the tubing string and then repeating the cycle of operation, a valve controlling discharge of the elevated production fluid from the tubing string, means for automatically opening and closing the last mentioned valve at predetermined time intervals, and means for independently adjusting the time intervals during which said last mentioned valve is open and closed respectively.

25 7. In combination, a tubing string for a well bore, means for admitting production fluid from the well bore to the tubing string, valvular means in the well rotatably movable through a plurality of open positions to permit various rates of admission of displacement fluid to the tubing string, an actuator engaging said valvular means so that the actuator is adapted for reciprocation relative to the valvular means but rotates the valvular means through its plurality of open positions responsive to step-by-step rotation of the actuator, a pin and slot operating connection for rotating the actuator step-by-step responsive to successive reciprocations of the actuator, and means controlled from the earth's surface for reciprocating the actuator.

30 8. In combination, a tubing string for a well bore, a valve in the well bore controlling admission of displacement fluid to the tubing string, a valve controlling admission of production fluid to the tubing string, the said valves being adapted for dependent automatic operation responsive to pressure differential for admitting production fluid to the tubing string while shutting off admission of displacement fluid and then trapping production fluid in the tubing string and admitting displacement fluid for elevating the trapped production fluid and then repeating the cycle of operation, valvular means in the well rotatably movable through a plurality of open positions to permit various rates of admission of displacement fluid via the open displacement-fluid-admitting valve, an actuator engaging said valvular means so that the actuator is adapted for reciprocation relative to the valvular means but rotates the valvular means through its plurality of open positions responsive to step-by-step rotation of the actuator, a pin and slot operating connection for rotating the actuator step-by-step responsive to successive reciprocations of the actuator, and means controlled from the earth's surface for reciprocating the actuator.

35 9. In combination, a tubing string, a valve controlling admission of displacement fluid to the tubing string, a valve controlling admission of production fluid to the tubing string, the said valves being adapted for dependent automatic operation for opening the second mentioned valve and admitting production fluid to the tubing string, while closing the first mentioned valve and shutting off admission of displacement fluid, and then closing the second mentioned valve

and trapping production fluid in the tubing string, while opening the first mentioned valve and admitting displacement fluid for elevating the trapped production fluid for discharge via the tubing string, and then repeating the cycle of operation, a valve controlling discharge of the elevated production fluid from the tubing string, and means for alternately opening and closing the last mentioned valve, so that said last mentioned valve is opened for discharge of said elevated production fluid, and is closed at a time at which the second mentioned valve is open, for increasing the pressure in the tubing string so as to close the second mentioned valve.

10. In combination, a tubing string, a valve controlling admission of displacement fluid to the tubing string, a valve controlling admission of production fluid to the tubing string, the said valves being adapted for dependent automatic operation for opening the second mentioned valve and admitting production fluid to the tubing string, while closing the first mentioned valve

and shutting off admission of displacement fluid, and then closing the second mentioned valve and trapping production fluid in the tubing string, while opening the first mentioned valve and admitting displacement fluid for elevating the trapped production fluid for discharge via the tubing string, and then repeating the cycle of operation, a valve controlling discharge of the elevated production fluid from the tubing string, means for alternately opening and closing the last mentioned valve, so that said last mentioned valve is opened for discharge of said elevated production fluid, and is closed at a time at which the second mentioned valve is open, auxiliary means controlling admission of fluid pressure to the tubing string, and means for closing said auxiliary means while said last mentioned valve is open, and opening said auxiliary means for a time interval while said last mentioned valve is closed, for increasing the pressure in the tubing string so as to close the second mentioned valve.

ROBERT P. MILLER.
